UNITED STATES PATENT OFFICE.

MARCELLUS J. WILLIAMS, OF PORTLAND, OREGON.

TRACTION-ENGINE.

1,170,031.

Specification of Letters Patent.

Patented Feb. 1, 1916.

Application filed February 5, 1915. Serial No. 6,384.

To all whom it may concern:

Be it known that I, MARCELLUS J. WILLIAMS, a citizen of the United States, and a resident of Portland, county of Multnomah, 5 State of Oregon, have invented a new and useful Improvement in Traction-Engines, of which the following is a specification.

My invention relates to improvements in traction engines of the heavy-duty type and 10 particularly to machines of this type which are used in localities where the soil is of a sandy character.

One of the main objects of my invention is to provide an articulated traction engine 15 of high tractive efficiency and of such form that it will conveniently fit the unevenness of any ground over which it may travel without causing torsional stress in any of the parts.

20 Another object of my invention is to provide means for driving all wheels of this traction engine simultaneously.

A further object of my invention is to provide a traction engine of this type which will 25 have all bearings located at considerable height above the ground so that they will not be so susceptible to catching sand, which is so harmful to such bearings.

Further objects of my invention consist 30 in making the frame of my traction engine of independent units for the front and rear wheels respectively, connecting such frame units by a universal joint and including in the latter means adapted to permit the relative longitudinal movement of one frame 35 unit with respect to the other.

A still further object of my invention is to provide both power and manual steering means for controlling the direction of travel 40 of the machine.

My invention further has for its particular object to eliminate to a great extent the intricate construction so common to heavy-duty traction engines.

45 Some of the particular features of my invention are the means provided which will differentiate motion among the rear wheels; the universal joint between the two frames of the machine, which permits the latter to 50 accommodate itself to the unevenness of the ground over which it is running; and the construction which allows certain projecting parts to be removed from the body of the machine when the latter is to be used for 55 road-work instead of field work.

All features of my invention are fully

shown and described in the accompanying drawings, in which—

Figure 1 is a plan view of the tractor, the motor and speed-changing mechanism being shown in dotted lines; Fig. 2 is a longitudinal section taken approximately on the line 2 of Fig. 1; Fig. 3 is a larger scaled side elevation showing the controlling means for operating the friction clutches which transmit power to the front wheels; Fig. 4 is a 60 sectional elevation of the ratchet clutch by which the rear wheels are driven in one direction and permitted to idle in an opposite direction; Fig. 5 is a sectional view taken 65 approximately on the line 5—5 of Fig. 4, and Fig. 6 is a sectional view taken approximately on the line 6—6 of Fig. 1, showing a detail of construction.

70 My tractor comprises two connected sections, the front section A and the rear section B. Referring now to the front section A; a frame *a* is provided on its lower side with bearings *b*, in which is mounted the axle *c*. Wheels *c'* are rotatably mounted 75 on said axle *c*, and bolted to the side face of each wheel is a sprocket *c*². A transverse shaft, *d*, made with floating ends *d'* is rotatably mounted in bearings *d*² on the front 80 end of the frame *a*. Fixed on said shaft *d*, is a bevel gear *e*, and on the floating ends *d'* are fixed sprocket wheels *f*, the latter being 85 in alinement with the sprockets *c*² and connected to them by a chain drive *f'*. Spring-controlled friction clutches *g*, *g'* of standard make connect the shaft *d*, with the floating ends *d'*, and are adapted to transmit motion 90 from the driven portion of said shaft upon which the bevel gear *e*, is fixed to the floating ends *d'* upon which the sprocket 95 wheels *f* are fixed. The clutch levers *h*, *h'* extend horizontally and have affixed to their ends cables *i* and *i'* respectively which run over sheaves *j*, *j'*, *j*², *j*⁴, and *j*⁵ to a lever *k*. The sheaves *j*, *j'* are single pulleys mounted 100 on opposite sides of the front frame *a*, the sheave *j*² comprises two independent pulleys mounted on a common pivot at the rear center of the front frame, the sheave *j*⁴ comprises two independent pulleys mounted on a pivot on the front center point of the rear frame, and the sheave *j*⁵ comprises two independent pulleys mounted on the front end of the rear frame. The lever 105 *k*, is mounted on the frame *m*, of the rear section B of the traction engine, (see Fig. 3) being fulcrumed on the pivot *m'* 110

and the cables i , i' running over the sheaves above mentioned, are made fast to said lever at points above and below said fulcrum respectively. In this way, when the lever k is thrown backward, the cable i will be slackened and a pull exerted on the cable i' , and conversely when the lever k is thrown forward, the cable i' will be slackened and a pull will be exerted on the cable i . The 10 pull on either cable will throw out the corresponding clutch to the handle of which said cable is connected. In the rear center portion of the frame a , are the trunnion supports n , in which the vertical trunnions 15 of the universal joint member n' are supported. See Fig. 2. Fixed to said member n' , is a longitudinally extending shaft n^2 , which has a bearing in the members m^2 and m^3 , of the rear section frame m . Collars n^3 20 and n^4 on said shaft n^2 are adapted to abut against the corresponding face of the frame members m^2 and m^3 and thereby limit the longitudinal movement of the shaft n^2 relative to said rear section B.

25 Mounted on the rear section frame m , is a motor, o , the speed changing mechanism being indicated by o' and the operating lever for same by o'' . On the rear end of the propeller shaft of said motor is a gear p , meshing with and driving a gear p' , the latter fixed on a longitudinal shaft q . The shaft q , is mounted in bearings q' , and the motor o is elevated to the proper position for allowing the shaft q to be carried forward 30 along the longitudinal center line of the machine over the frame m . On the frame a , of the front section A, are bearings r' , in which is journaled a shaft r . A bevel gear r^2 fixed on the forward end of this shaft 35 meshes with and is adapted to drive the bevel gear e of the shaft d . A flexible intermediate link s , connecting the shafts q and r through the universal joints s' and s^2 respectively forms the driving connection between such shafts. Said link s , is made in 40 sections s^3 and s^4 , the latter being adapted to telescope into the former, but having no rotary movement relative thereto.

The rear axle t , of the traction engine, is 45 fixed in bearings t' , under the frame m , as shown in Fig. 2. Rotatably mounted on the axle t , are the rear wheels u . Bolted on the side face of each wheel u , is a ratchet u' , the latter being made with a hub u^2 encircling the axle t . A sprocket wheel v , made in the form of a housing (see Figs. 4 and 5) 50 is rotatably mounted on the hub u^2 of the ratchet u' , a ball bearing u^3 being interposed between the bearing parts for the purpose of reducing friction.

55 Pawls t' are pivoted on the studs t^2 and springs t^3 normally thrust the pawls into engagement with the teeth of the ratchet u . A jack-shaft w , is rotatably mounted in 60 bearings w' on the frame m . A differential

gearing connection indicated by w^2 forms the transmitting medium between the shaft q and the jack-shaft w . Fixed on the shaft w , are sprocket wheels w^3 in line with the sprockets v , and connected to them by a 70 chain drive w^4 .

The projecting side portions of the rear section B, that is, the parts projecting outside the longitudinal sides of the front section A, are adapted for use only when heaviest field service is required, and when the machine is to be used on road-work, these projecting portions are not used, as they would make the machine too wide for convenient use. The manner in which these 80 portions are removably fixed to the body of the machine is shown in Figs. 1 and 6. The frame members y are provided with cover-plates y' adapted to be bolted to the members of the frame m , by the bolts y^2 . The 85 wheels z are similar in construction to the wheels u , and their axles z' are removable from the outer bearings in which the main rear axle t is mounted. The auxiliary shafts 90 z , have their outer ends journaled in the 90 bearings 8 on the frame y , and carry the sprocket wheels 9 , which are in line with and connected to the sprocket clutches of the wheels z , by a chain drive 10 . The inner ends $3'$ of the auxiliary shafts z are squared, 95 and adapted to be inserted in squared axial holes in the ends of the jack-shaft w . See Fig. 6. In this way, when the auxiliary frames are used, a positive drive will be transmitted to the wheels z in the same manner it would be if the auxiliary frames were 100 integral parts of the machine.

The steering column 12 , is rotatably mounted in the bearing 13 , and its lower end is formed with a worm 14 , (see Fig. 2). A 105 shaft 15 is journaled transversely of the machine under the front end of the frame m , and fixed thereon is a worm gear 16 , adapted to be turned by the worm 14 of the steering column 12 . Spools 17 , and $17'$ are fixed on 110 opposite ends of the shaft 15 , and steering chains 18 and $18'$ connected to the sides of the front frame a , are adapted to be wound in opposite directions on the spools 17 and $17'$ whenever the steering wheel is turned. 115

The general operation of my machine is as follows: When the machine is traveling forward or backward in a straight line, all wheels are positively driven. Let us suppose that the operator wishes to turn to the right, having reference to Fig. 1. He will throw the lever k back, thereby exerting a pull on the cable, i' and slackening the cable i . The clutch g' will thereupon be disengaged and the corresponding floating end d' of the shaft d , will be allowed to idle. The drive on the other wheel c' will then turn the machine. If it is desired to turn on a shorter radius than can be accomplished by the manner above described, the operator 120

125

120

130

will turn the steering wheel so as to wind up the chain 18' and unwind the chain 18. The front section A will thereupon turn to the right, and the differential action among the rear wheels, due to the differential gearing w^2 , and the ratchet clutches shown in Figs. 4 and 5, will allow all of said wheels to idle except the outside one on the side to which the turn is being made. The telescoping universal joint link s, allows continuous transmission of power from the motor o, to the front section A, regardless of the movements of the machine. The universal joint which connects the tractor sections A and B, will allow each section to readily adapt itself to the contour of the ground over which said traction engine is running at any time without producing torsional stresses in the frames or transmission shafts. This feature itself is one of the important parts of my invention. When the machine is to be driven backward, all of the rear wheels will idle, and the drive will be placed wholly on the front wheels. Whenever the traction engine is to be used for road work, the bolts y^2 are removed, and the projecting portions of the rear section B, as previously mentioned, may be readily disconnected from the body of the machine.

39 I claim:

1. In a self-propelling vehicle, a frame consisting of independent units for the front

and rear wheels respectively, a joint connecting such frame units, manual steering mechanism for the front frame-unit, power operated driving means connected to both the front and the rear wheels, and adapted also for driving the front wheels independently of each other, and means included in said connecting joint permitting the relative longitudinal movement of one frame-unit with respect to the other, whereby the manual steering connections of the front wheel frame unit are relatively adjusted to permit the action of the power-driven steering means.

2. In a self-propelling vehicle, a frame consisting of independent units for the front and rear wheels respectively, a joint connecting such frame-units, and a member included in said connections relatively telescopic in one of said frame-units to permit the variation of the distance said frame-units are spaced apart by said joint, manual steering mechanism for the front frame-unit, and power operated driving means connected to both the front and the rear wheels, and adapted also for driving the front wheels independently of each other.

MARCELLUS J. WILLIAMS.
